GARMENT HANGER

Robert Phillips, Roslyn, N.Y., assignor to Bernard Plastics Molding Corp., Woodside, N.Y., a corporation of New York

Filed Sept. 21, 1966, Ser. No. 3,948

Term of patent 14 years

(Cl. D80—8)

FIG. 1 is a front elevational view of a garment hanger showing my new design;

FIG. 2 is a cross sectional view taken on line 2—2 of FIG. 1; and

FIG. 3 is a fragmentary rear elevational view of the center cross bar.

I claim:

The ornamental design for a garment hanger, as shown.
